UNITED STATES PATENT OFFICE.

ALBERT NYVALL, OF NEW YORK, N. Y.

CARD-INDEX.

1,116,909.

Specification of Letters Patent.

Patented Nov. 10, 1914.

Original application filed July 9, 1912, Serial No. 708,437. Divided and this application filed December 13, 1913. Serial No. 866,406.

To all whom it may concern:

Be it known that I, ALBERT NYVALL, a citizen of the United States of America, and a resident of the borough of Manhattan, 5 city, county, and State of New York, have invented certain new and useful Improvements in Card-Indexes, of which the following is a specification.

My invention relates to an improvement 10 in card indexes and is a division of my application Serial No. 708,437, filed July 9, 1912.

My invention has as its objects the provision of means obviating the use of projecting tabs as at present provided as guides to the index and substituting therefor grooved depressions with guide cards extending into said grooved depressions but not above the top edge of the cards, as will hereafter more 20 clearly appear; the provision of means for detecting the misfiling of a card and locating the correct position thereof, and the provision of means for ascertaining the absence of a card from the index and its correct 25 location.

A serious inconvenience and objection to card indexes as at present in use is that the projecting tabs of the guide cards break off or are torn off by the rubbing of the arm of 30 the user of the index over the cards, the placing of a book or other object on top of the cards, or otherwise. Another objection is that card index boxes cannot be stacked one upon another, owing to the presence of 35 the projecting tabs and consequently when in use are spread about on desks or tables when, if the tops of the cards were flush, such would not be necessary and much space would be economized. Furthermore, 40 if a card is misplaced, much confusion results, and, in a large index, it may be practically impossible to find the missing card. This necessitates the employment of high 45 class clerks for filing in order to prevent mistakes as far as possible. Again, if a card is removed from the file its absence is difficult, if not impossible, of ready detection. By my invention I do away with all of 50 these difficulties. As I provide no projecting tabs there are none to be broken off and as the tops of the cards in my system are flush with the guide cards, the boxes may readily be stacked one upon another. A 55 casual glance over my card index by an executive will at once detect the misfiling of a

card and indicate the proper place for it, thus making it possible to employ inexperienced clerks for the work and furthermore a glance will tell whether a card has been removed and from where.

In the following I have described, in connection with the accompanying drawings, several illustrative methods of practising my invention, the features thereof being more particularly pointed out hereinafter 60 in the claims.

In the drawings, Figure 1 is a perspective view illustrating one form of my invention; Fig. 2 is a perspective view, partly broken away, of a similar bundle of cards showing a 70 means for noting the absence of a card, as well as means for locating the missing card if it has been misfiled somewhere else in the index; Fig. 3 is a perspective view illustrating another form of my invention; and Fig. 75 4 is a perspective view, partly broken away of a similar bundle of cards illustrating the same features as Fig. 2.

Similar letters of reference indicate similar parts throughout the several views.

In the drawings, *a* indicates the box or drawer adapted to contain the cards. In the form in which my invention is illustrated in Figs. 1 and 2, I have shown the cards as numerically arranged, the cards being provided with nine notches and a blank each, each blank in this instance being both an index and a card locating blank. The extreme right hand groove *k*, as shown, is indexed in multiples of ten and the other 80 grooves from left to right are indexed in integers from 1 to 9 serially. The index number of each card appears upon the blank space of each card as shown at *m* in Fig. 2, so that for example, the first card will have 95 a blank at the left hand end numbered 1 followed by nine notches from left to right, the second card will have a notch at the left hand end followed by a blank numbered 2 and in turn followed by eight notches and 100 so on, the blanks projecting upward into the grooves of their respective numbers, that is, number 1 blank projecting upward into number 1 groove, number 2 blank projecting upward into number 2 groove and so on, 105 each group of ten cards being arranged and numbered as described, and then repeated as often as the size of the card index as a whole requires. It will be observed that each card has its individual place and that 110

if any card is misfiled it not only leaves a vacancy in the place where it belongs, as shown at *n* in Fig. 2, but also shows an extra card in the place where it has been misfiled, as shown at *p* in Fig. 2, thus making it possible both to detect the fact that a card is missing and where it has been placed if it is in the file. In this form the upper margins of the cards, where uncut, are flush with each other thus forming a plane upper surface without projections to be broken off.

In the form in which my invention is illustrated in Figs. 3 and 4, I have shown the cards arranged so as to combine the benefits of both an alphabetical index and a numerical system. In this case the cards are provided with ten notches and a blank each, instead of nine notches and a blank as shown in connection with Figs. 1 and 2. The general arrangement is the same as described in connection with Figs. 1 and 2 with the exception that the additional groove *d'*, serves as a main guide or index groove. In the form shown in Figs. 3 and 4, if additional cards are needed under any index letter, they should preferably be added in multiples of ten. I have found it convenient to begin the numerical system under each letter with the numeral "1", but of course any desired arrangement could be used. The guide or index cards *c', c'* in Figs. 3 and 4 are cut similarly to the other cards excepting that they have a blank projecting upwardly into the groove *d'* as shown in Fig. 3. They may also be of contrasting color to the other cards. By this means any number of cards may be included under each index letter with the advantages of my invention as hereinbefore pointed out.

It is clear in my system that the filing may be done by unskilled clerks, and the mistakes, if any, readily ascertained by a mere inspection.

As it is obvious that the details as illustrated may be greatly varied without departing from the principle of my invention, I do not restrict myself to such details further than the scope of the appended claims demand.

What I claim and desire to secure by Letters Patent is:

1. A card index comprising a series of cards arranged in groups, said cards being provided with notches in their upper edges, said notches having a normal relationship to the notches in the upper edges of the cards of the same group, and having otherwise an unnotched upper edge adapted to act as an index in the grooves formed by the registering of certain of said notches, the misplacing of the cards of one group with reference

to the cards of another group being indicated by the abnormal position of said unnotched upper edges relative to each other.

2. A card index comprising a series of cards arranged in groups, said cards being provided with notches in their upper edges, said notches having a normal relationship to the notches in the upper edges of the cards in the same group, but having otherwise an unnotched upper edge adapted to act as an index in the grooves formed by the registering of certain of said notches, and individual identifying means for each of said cards, said unnotched upper edges having a normal relationship to each other in the group with which they are associated, the misplacing of any card of one group with reference to the cards of another group being indicated by the abnormal position of said unnotched upper edges relative to each other in said latter group and in its normally associated group.

3. A card index comprising a plurality of cards, each of said cards being provided with a plurality of notches and a blank in its upper edge, said notches being arranged to register with all but one of the notches in the adjacent cards and said blank being arranged to register with said remaining notch.

4. A card index comprising a series of cards arranged in groups, each card of each group being provided with a plurality of notches and a blank in its upper edge, said notches being arranged to register with all but one of the notches in the adjacent cards and said blank being arranged to register with said remaining notch, the misplacing of the cards in the series being indicated by the abnormal relationship of said blanks with reference to each other.

5. A card index comprising a series of cards each card having a series of notches in its upper edge, said notches being adapted to register to form grooves with the notches of the adjacent cards, and an index portion on one of said cards projecting into each of said grooves but not above the upper edge of the cards, said index portions having a normal relationship to each other, whereby the misplacing of each card in the system with reference to the other cards is indicated by an abnormal arrangement of said index portions respectively to each other.

In testimony whereof I have signed this specification in the presence of two subscribing witnesses.

ALBERT NYVALL.
